TURBINE BLADE SHROUD FASTENING

Clarence C. Franck, Swarthmore, Pa., assignor
to Westinghouse Electric & Manufacturing
Company, East Pittsburgh, Pa., a corporation
of Pennsylvania

Application February 14, 1942, Serial No. 430,842

2 Claims. (Cl. 253—77)

The invention relates to turbine blading and it has for its object to provide an improved method and construction of turbine blades permitting of their connection to a rotor so that full advantage may be taken of the mechanical strength of the structure in resisting forces to which the blades may be subjected and without there being any locked-up stresses in the blading incident to assembly and attachment thereof to form the blade row.

It is common practice to have the blades of a row connected to a rotor by having inwardly-facing shoulders formed on the rotor and cooperating with outwardly-facing shoulders formed on the blade roots and to have the blades connected by a shroud or lashing structure. With the shroud or lashing connected, the root shoulders may not bear against the rotor shoulders uniformly; and, in consequence, the blade structure, particularly the shroud or lashing construction thereof, may be overstressed or unevenly stressed when centrifugal forces are developed in the blades. In accordance with the present invention, there is employed a shroud or lashing construction which permits of each blade root shoulder bearing firmly against the cooperating rotor shoulder, whereupon, with this relation established, the shroud or lashing construction is completed without the introduction of any deformation or stress. The improved method, therefore, inherently requires blades each of which is provided with the usual root and with a shroud or lashing element, the shroud or lashing elements of adjacent blades having overlapped portions which are spaced-apart radially to a small extent after initial assembly of the row of blades on the rotor, and the latter is rotated at a speed of about twenty per cent above normal so that the roots and all parts will assume a natural position with all seating or shoulder surfaces firmly engaged to resist forces to which the blades may be subjected. After spinning of the rotor at an overspeed for the purpose just stated, spacer members of suitable thickness are introduced between each pair of lapping portions of the shroud or lashing elements and each pair of lapping portions and the spacing member are secured together.

A further object of the invention is to provide a turbine rotor having a row of blades connected thereto by means of cooperating rotor and blade root shoulders and it has for an object to provide the blades with lapping portions such that, with the blades of the row assembled with the shoulders thereof engaging the rotor shoulders, lap-

ping portions of adjacent blades will be in overlapped and spaced-apart relation together with spacing members arranged between each pair of overlapping portions, each spacing member having a thickness conforming to that of the space, and rivets for connecting the overlapping portions and the intervening spacing elements.

These and other objects are effected by the invention as will be apparent from the following description and claims taken in connection with the accompanying drawings, forming a part of this application, in which:

Fig. 1 is a fragmentary sectional view of the improved blading;

15 Fig. 2 is a fragmentary plan view looking down on the shroud construction of Fig. 1;

Fig. 3 is a sectional view taken along the line of III—III of Fig. 1;

20 Fig. 4 is a detail isometric view of the outer end of one of the blades and showing the lapping portions thereof extending in opposite directions;

25 Fig. 5 is a fragmentary elevational view showing overlapped elements or portions connected to the blades and connected so as to form a lashing for the latter;

Fig. 6 is an enlarged detail view of one of the blades illustrated in Fig. 5 and showing the lashing in section;

30 Fig. 7 is a sectional view taken along the line VII—VII of Fig. 6;

Fig. 8 is a sectional view taken along the line VIII—VIII of Fig. 7; and

Fig. 9 is a view similar to Fig. 8 but showing a 35 modified form of lashing.

In the drawings, the blades 11 forming a row are secured to the rotor 9 by means of inwardly-facing rotor shoulders 12 cooperating with outwardly-facing shoulders 13 formed on the blade roots 14. While the cooperating shoulders may be provided by any suitable rotor and blade root structure, as shown in Fig. 3, the rotor has a blade groove 15 formed with inwardly-extending annular flanges 16 providing the inwardly-facing shoulders 12 and each blade root is formed to fit the groove, the root having laterally-projecting portions 17 providing the outwardly-facing shoulders 13.

The blades are formed with shroud or lashing elements, which, upon assembly of the blades in a row have spaced-apart lapping portions.

In Figs. 1 to 4, inclusive, there is shown a row of blades having a shroud construction, at 19, comprised by lapping portions 20 and 21, spacers 22 arranged between the overlapped

lapping portions of adjacent blades, and rivets 23 for connecting each pair of overlapped portions 20 and 21 and the intervening spacing member 22.

As shown, each lapping portion 20 is an overlapping one and each portion 21 is an underlapping one; and, except for two blades 11a and 11b in Figs. 1 and 2, the remaining blades 11 are similar, each of the latter having an overlapping portion projecting from one face thereof and an underlapping portion projecting from the other face thereof.

The blade 11a is provided only with underlapping portions 21 and the blade 11b has only overlapping portions 20, the reason for this special construction being to permit of assembly of the last blade 11b. Assuming the blade row to be assembled with the exception of the last blade 11b and with the blade 11a and a blade 11 at opposite sides of the filling opening, then it will be apparent that as the adjacent sides of these blades have underlapping portions, the blade 11b with overlapping portions 20 may be readily inserted to bring the lapping portions thereof into overlapped relation with respect to the lapping portions of the adjacent blades 11a and 11.

With the blade row assembled, the rotor or disk is rotated at a desired speed above normal, for example, about twenty per cent above normal, the effect of overspeeding being that the blades are constrained thereby each to assume its natural position with its root shoulders firmly engaging the rotor shoulders.

After overspeeding, spacing members or shims 22 are inserted in the spaces 24, each shim or spacer being individually fitted to its space, and each pair of overlapped portions and the intervening spacer or shim of fitted thickness are secured together by any suitable means, as by a rivet 23.

In Figs. 6 to 9, inclusive, there is shown a structure wherein the lapping portions 20a and 21a, the spacers 22a and the rivets 23a cooperate to provide a lashing construction instead of a shroud construction, as in Fig. 1. Preferably, as shown in Figs. 6, 7, and 8, the lapping portions 20a and 21a are formed integrally with the blades 11a. In Fig. 9, instead of the lapping portions being formed integrally with the blades, they are connected thereto by welding, that is, the lapping portions 20b and 21b are connected to the blades 11b by welds, at 25.

The lashing construction shown in Figs. 6 to 9, inclusive, is also arranged to be finally connected after preliminary overspeeding of the rotor, that is, after overspeeding, the spacers 22a are formed to fit the individual spaces between overlapping portions 20a and 21a, after which the overlapped portions and the intervening spacer are riveted together by means of a rivet 23a.

While the invention has been shown in several forms, it will be obvious to those skilled in the art that it is not so limited, but is susceptible of various other changes and modifications without departing from the spirit thereof, and it is desired, therefore, that only such limitations shall be placed thereupon as are specifically set forth in the appended claims.

What is claimed is:

1. In a turbine, a row of blades; each blade including a root element and each root element having outwardly-facing shoulders; a rotor carrying the row of blades and provided with inwardly-facing shoulders for cooperation with the root shoulders; and a shroud construction for the row of blades comprising oppositely-extending lapping portions formed integrally with the tip of each blade and the lapping portions of adjacent blades overlapping in spaced-apart relation with the root shoulders of the blades engaging the rotor shoulders, filler pieces fitting the spaces between overlapped portions, and rivets connecting the overlapped portions and the intervening filler pieces.

2. The method of assembling a blade row structure which comprises providing a rotor having inwardly-facing shoulders, providing blades each of which has outwardly-facing root shoulders and circumferentially-extending elements having lapping portions, assembling the

40 blades in a row on the rotor with the root shoulders thereof in opposed relation to the rotor shoulders and with the lapping portions of adjacent blades in overlapped and spaced-apart relation, rotating the rotor at a speed a desired amount above normal speed to cause firm engagement of the blade root and rotor shoulders, providing for the space between each pair of overlapping portions a spacing member whose thickness conforms to that of the space, and fastening together each pair of overlapped portions and the intervening spacing member.

CLARENCE C. FRANCK.
